MANIFOLD APPARATUS

Raymond J. Branson, Tulsa, Okla., assignor to
 McNamar Boiler & Tank Company, Inc., Tulsa,
 Okla., a corporation of Oklahoma

Application August 12, 1946, Serial No. 689,992

3 Claims. (Cl. 62—1)

1

This invention relates to a manifold, and more particularly, but not by way of limitation, to a manifold adapted for use with a storage tank housing liquified petroleum gases.

In recent years, liquified petroleum gases have come into widespread use, particularly in rural communities where it is necessary to have a commercial fuel for the operation of farm equipment, home heating and lighting, and other necessary utilities, and where the source of other commercial fuels such as natural gas or the like are not readily available. In the use of liquified petroleum gases, it is necessary to provide a storage tank which must be refilled from time to time. Liquified petroleum gases such as propane and butane and the like are highly volatile and considerable difficulty is involved in filling the storage tanks therefor to keep the liquid under compression away from the vapor line and the possibility of igniting, especially since the volatile liquids expand very rapidly and if allowed to come in contact with a vapor conduit leading to a stove or the like will ignite and create considerable danger.

The present invention contemplates a manifold for use with an apparatus for filling a liquified petroleum gas storage tank in such a manner to assure safety during the filling operation and prevent the possibility of igniting the volatile liquids by contact with the vapor line.

It is an important object of this invention to provide a manifold adapted for use in filling storage tanks with liquified petroleum gases wherein the volatile liquid is permitted to flow into the tank into contact with liquid and not the expanding vapors therefrom, thereby preventing spraying liquid into a hot tank and causing a rapid expansion into vapors and consequent losses.

And still another object of this invention is to provide a manifold utilized with an apparatus for filling a storage tank with liquified petroleum gases wherein the liquid is introduced directly into the tank without any possibility of contacting expansion vapors of the compressed liquid.

And another noteworthy object of this invention is to provide a manifold utilized in the filling of liquified petroleum gases in a filling tank which is so constructed and arranged to permit a flow from the storage tank back to a filling truck when the pressure in the tank is slightly greater than that in the truck during the necessary replacement of parts and the like whereby the vapors are preserved by removing the liquid from the tank.

Other objects and advantages of the invention

2

will be evident from the following detailed description, read in conjunction with the accompanying drawings, which illustrate my invention.

In the drawings:

Figure 1 is a vertical sectional elevational view taken on lines 1—1 of Figure 2 and having certain parts in elevation for clarity.

Figure 2 is a plan view of the invention.

Figure 3 is an elevational view partly in section taken on lines 3—3 of Figure 2.

Referring to the drawings in detail, reference character 2 designates a manifold head comprising a vertically elongated body member 4 having a threaded aperture 6 in the lower portion 15 thereof receiving a threaded nipple 8 in turn welded at 10 to a liquified petroleum gas storage tank 12. The upper portion of the manifold body 4 is provided with a threaded aperture 14 communicating with a chamber 16 in turn communicating with a threaded bore 17 providing communication with a lower chamber 18 which is in direct communication with the outlet aperture 6 and nipple 8. A cylindrical filling pipe 20 is secured in the threaded bore 17 and extends therefrom into proximity with a lowermost portion of a tank, as clearly shown in Figure 1 in order to baffle chamber 16 from 18. Figure 1 shows a fragmentary horizontal tank while Figure 3 shows a fragmentary spherical tank. It will be obvious that the manifold structure may be utilized from any type of storage tank for housing liquified petroleum gases, and while the installation is preferably above the ground, it will be understood that the tank can be located beneath the surface of the ground, which is sometimes desired.

The chamber 18 is formed by a pair of oppositely disposed projections 22 and 24 extending outwardly from the elongated body member 4. The flanges or projections are provided with threaded outlet apertures 26 and 28. A vapor line control valve 30 is secured in aperture 26, while a vapor return valve 32 is secured in the aperture 28 for purposes that will be hereinafter set forth. A threaded aperture 34 is provided in the upper portion of each of the projections 22 and 24 and are adapted to receive pressure relief valves 38, as clearly shown in Figures 1 and 2. The inlet bore 14 is provided with a filler valve 40 acting as a check valve against the back pressure of the volatile liquid during the filling of the tank 12. This valve is necessary to prevent an expansion of the liquid in the filling tube 20. A pressure gauge 42 is secured in a threaded aperture 43 of the member 4, as clearly shown in Figures 2 and 3.

Referring to Figure 3 the body 4 is provided with an outwardly projecting member 45 disposed at right angles to members 22 and 24 and has a threaded bore 44 adapted to receive a liquid discharge valve 46 for a purpose as will be hereinafter set forth. The valve 30 is provided with a flanged nipple 48 providing communication between the chamber 18 and a vapor conduit line 50 extending into communication with a pressure regulator 52 for a purpose as will be hereinafter set forth.

Operation

In operation the manifold 2 through valve 40 is adapted to be connected with a conduit (not shown) of a filling truck containing liquified petroleum gases, such as propane, butane or the like, so that the volatile liquids may be pumped into the storage tank 12. It will be apparent that the volatile liquids flow through the valve 40 into the chamber 16 and downward through the filling cylinder 20 to be discharged at a point in proximity of the lower portion of the tank 12. The point of discharge for the volatile liquids is important in that it allows for a distortion or mixing of the incoming liquids with the liquids already in the tank. Under certain climatic conditions, particularly the summer months, it is often desired to reduce the pressure of the liquified petroleum gases due to the heat and provide a mixture or blend of butane and propane and the like. For example propane may be added into a storage tank containing butane, and the discharge point of the cylinder 20 causes a turbulence of the liquids to provide a blend. Furthermore, the cylinder 20 baffles the inlet chamber 16 from the vapor chambers 18 so that the volatile liquid discharging from the pipe 20 cannot in any manner contact the expanding vapors rising from the compressed liquid in the tank 12 and discharging through the nipple 6 into the chambers 18.

This also has an important advantage in that the filling liquid discharges into the tank 12 into liquid, and is prevented from the possibility of discharging through the chamber 18 and vapor fuel conduit 50 where it could ignite with a utility heater or the like and cause considerable damage.

The expanding vapors discharge from the chambers 18 through the nipple 48 and conduit 50, and hence through the pressure regulator for determining the amount of pressure of the vapor to be discharged, and into an outlet conduit 56 leading directly to any appliance such as gas heaters, stoves, hot water heaters, motors, or the like, for consumption.

In addition to the safety feature the manifold 2 provides the member 45 and discharge valve 46, which is manually operated and when rotated to open position permits the removal of the volatile liquid from the tank 12 into chamber 16 to be discharged through a conduit 58 directly to a gasoline engine, motor, tractor or other farm equipment. The discharge of the volatile liquid from the tank 12 and through the conduit 58 is usually created by the compression of the liquid in the tank, however this discharge may be done by gravity or a suction pump depending upon the environment of the tank. The valve 46 provides one means of removing the liquid from the tank for auxiliary uses, however when it is desired to expedite removal of the liquid from the tank in case of emergency, such as tank leaks, or the like, the top valve 40

can be utilized wherein the liquid can be removed by a vacuum pump directly from the tank through cylinder 20 and valve 40.

Another additional feature of the manifold and valve arrangement is that during the filling operation the valve 32 is adapted to receive a connecting conduit (not shown) from the truck whereby the pressure between the filling truck (not shown) and the tank 12 may be equalized in order to assure that the volatile liquid can be pumped into the tank 12 without any danger of burning out the pumping equipment for the truck. It will be apparent that when the pressure between the tank and the truck is equalized the volatile liquids can be easily discharged into the tank 12. The connecting conduit (not shown) is usually provided with any conventional adapter (not shown) causing the valve 32 to remain in open position during the filling operation.

From the foregoing it will be apparent that the present invention provides a manifold apparatus wherein highly volatile liquified petroleum gases can be filled into a storage tank without any substantial danger of the volatile liquid discharging into the vapor fuel consumption line. Furthermore, the construction of the manifold apparatus is such to fill a storage tank wherein the volatile liquid is discharged in the tank directly into a liquid thereby preventing the spraying of the liquid onto the inner walls of the tank which are usually hot from the rays of the sun. This liquid to liquid contact prevents a rapid expansion of the vapors from the volatile liquids and thereby prevents considerable loss of the vapor fuel. Furthermore, the liquid to liquid filling arrangement particularly in the lowermost portion of the tank provides for a normal blending of variable liquified petroleum gases when desired. In addition the manifold apparatus provides for an auxiliary outlet for the volatile liquid when it is desired to use the liquified petroleum gas as a fuel directly consumed by the conventional farm equipment, such as tractors, gasoline engines, and other equipment. Furthermore, the manifold apparatus provides for an expeditious removal of the volatile liquids from the tank in case of emergency.

I claim:

1. In a manifold apparatus adapted for use with a storage tank housing liquified petroleum gases, and comprising an elongated body having an axially disposed chamber for the passage of the incoming liquified gases therethrough to the tank, horizontally disposed chambers receiving the expansion vapors of the liquified gases in the tank, a valve controlled conduit connecting with one of said horizontally disposed chambers and permitting discharge of said vapors for fuel consumption, elongated means extending into the tank and communicating with the axial chamber and preventing contact of the liquified gases with the vapor chambers, means communicating with one of the vapor chambers to permit equalization of the pressure of the tank during the filling operation, and means communicating with the axial chamber permitting discharge of liquified gas therefrom.
2. In a manifold apparatus for filling a storage tank adapted to house liquified petroleum gases, and comprising an elongated body having an axially disposed chamber for passage of incoming liquified gases to the tank, means providing communication between the axial chamber and the tank, horizontally disposed chambers

receiving the expansion vapors of the liquefied gases in the tank, a valve controlled conduit connecting with one of said horizontally disposed chambers and permitting discharge of said vapors for fuel consumption, valve means disposed in at least one of said horizontal chambers to permit equalization of the fluid pressure in the tank during the filling operation, and an auxiliary valve means communicating with the axial chamber providing discharge of volatile liquid from the tank.

3. In a system for filling volatile liquids comprising a storage tank, a filling manifold cooperating therewith and comprising an inlet chamber, a plurality of vapor chambers disposed perpendicular to the inlet chamber and in communication with the tank, a cylindrical baffle providing communication between the inlet chamber and the tank and simultaneously precluding communication between the inlet chamber and the vapor chambers, a vapor fuel outlet

conduit connected with the vapor chambers, a valve connected with the vapor chambers and adapted to create equalization of the pressure in the tank during the filling operation, an auxiliary valve directly communicating with the inlet chamber and providing auxiliary discharge of liquefied gas from the tank.
